UNITED STATES PATENT OFFICE.

WRIGHT PRESTWICH AND ERNEST PRESTWICH, OF LAWRENCE, MASSACHUSETTS.

BUR-CARRIER FOR CARDING-MACHINES.

1,184,128.

Specification of Letters Patent. Patented May 23, 1916.

Application filed January 11, 1916. Serial No. 71,571.

To all whom it may concern:

Be it known that we, WRIGHT PRESTWICH and ERNEST PRESTWICH, citizens of the United States, and residents of Lawrence, 5 county of Essex, State of Massachusetts, have invented an Improvement in Bur-Carriers for Carding-Machines, of which the following description, in connection with the accompanying drawing, is a specification, like characters on the drawing representing like parts.

This invention relates to improvements in bur carriers for carding machines and the like and the object thereof is to provide a 15 bur carrier attachment which may be readily associated with standard carding machines or the like and in which the positions of the clearers for the bur pans may be more accurately positioned.

20 The invention disclosed herein comprises an improvement upon our prior Patent No. 924,879 granted June 8, 1909 which shows a carding machine equipped with a series of bur pans with independently operated carrier and clearers for each of the pans, the traverse shafts for said pans being supported upon brackets secured to the ends of the carding machine frame and adjustable vertically in respect thereto.

25 In the present invention the same type of traverse shafts and clearers for the bur pans may be used but means are provided to enable two of the traverse shafts to actuate simultaneously clearers for three or more 30 pans, thus reducing the expense of installation and economizing the cost of operation of the machine.

Another feature of the invention resides in so constructing the supporting means for 40 the traverse shafts as to provide means for adjusting the same both vertically and laterally thereby permitting the clearers to be positioned more readily and more accurately in respect to the pans.

45 Another feature of the invention consists in providing adjustable frictional means for controlling the action of the members for raising the clearers to inoperative position.

Other features of the invention will more 50 fully appear from the following description and the accompanying drawings and will be pointed out in the annexed claims.

In the drawings: Figure 1 is a side elevation of a portion of a worsted card showing the bur rolls and pans with a preferred embodiment of the present invention applied

thereto, Fig. 2 is an enlarged transverse detail view showing the bur clearers and the mechanism for operating the same. Fig. 3 is a vertical transverse sectional view 60 through one of the traverse shafts and the carriage for the clearers showing one of the clearers in elevation and illustrating the frictional device for controlling the position of the clearers. Fig. 4 is a side elevation of one of the brackets for supporting the traverse roll and a portion of its supporting standard, and, Fig. 5 is a detail view of one of the adjustable bunters for positioning the clearers.

73 Worsted cards are generally provided with a series of bur rolls in advance of the carding mechanism so arranged as to remove the burs from the material being carded and discharge the same into pans, 75 which extend transversely across the machine, the pans having open ends from which the burs are removed by an attendant by means of a long rake or scraper. When the material carded is dirty these burs collect 80 rapidly in the pans and a large portion of the time of the attendant is required to keep the pans clear, particularly if he is looking after a number of cards.

85 By the present invention automatic clearers are provided which discharge the burs from all of the pans preferably into a common chute which delivers them into a suitable receptacle, thus freeing the attendant from this amount of labor so that fewer 90 attendants are required.

The drawings illustrate the bur cleaning end of a standard card comprising end frames 1, 2 having suitable journals for the rotating mechanism which includes the bur 95 cylinder 3, the licker-in cylinders 4, 5, the top dividers 6, 7, the bottom divider 8, the feed stripper 9, the bur rolls 10, 11, 12, 13 and 14, shown as arranged in two groups, and corresponding bur pans 15, 16, 17, 18, 19 which 100 may be and are of substantially well known construction in worsted cards and operated in the usual manner, the burs being deposited by the bur wheels in the bur pans.

105 For clearness of illustration a large portion of the driving mechanism has been omitted but it will be understood that the same is of the character usual in worsted cards of this type.

110 The bur pans are preferably constructed of metal and are supported adjacent to the bur cylinders in such a manner that the burs

will be disposed directly in them. These pans are preferably provided at one end of the machine, or if desirable at both ends of the machine, with extensions or chutes three of which 20, 21 and 22 are illustrated in the drawing as discharging into a common chute 23 at the end of the machine which in turn delivers the burs into a suitable receptacle 24.

10 In the illustrative embodiment of the invention shown herein the automatic clearers are reciprocated in these chutes by means of rotating traverse shafts 25, 26 having oppositely disposed spiral grooves 27, 28 co-operating with the switches in the carriages 29, 30 which are slidably mounted upon the traverse shafts 25, 26, the clearers 31, 32 being supported by the carriages. It will however readily be understood that other 20 means may be provided for reciprocating the clearers within the scope of the present invention.

15 In order to adapt the automatically actuated clearers to any usual type of carding machine we have provided specially designed supporting mechanism for the traverse shafts adapted to be secured to any standard machine and in which the shafts may be adjusted to co-operate with the differently located bur pans of different types 30 of machines.

20 As illustrated herein the traverse shafts 25, 26 are journaled in suitable recesses 33 in the ends of substantially horizontal brackets 34 which are seated upon shoulders 35 in enlarged end portions 36 of standards 37 and secured thereto by bolt and slot connections. A convenient means for adjustably supporting the standards 37 illustrated 40 herein consists in providing screw threads 38 on the lower cylindrical portion of each standard passing the ends of the standards through eye-bolts 39 which may be conveniently secured to the main frame at any 45 desired point and providing nuts 40, 41 upon opposite sides of said eye-bolts to adapt the standards 37 to be raised and lowered any desired amount. It will be obvious that by thus providing for the vertical and 50 lateral adjustment of the traverse shafts the same may be positioned properly in respect to the bur pans whether a single shaft is used or whether two or more shafts are provided for the purpose of actuating the 55 clearers.

60 In our previous patent we disclosed a traverse shaft as co-operating with each of the bur pans. We have, however, found that three or more sets of clearers may be actuated from two traverse shafts with economy and efficiency. This may be accomplished as illustrated in the present invention by providing a bridge 42 or a series of bridges 42, 43 connected respectively to the carriages 29, 30 and supporting between them car-

riages or clearers co-operating with the intermediate bur pan or pans. As illustrated herein the bridges 42, 43 consist of iron brackets or strips which are connected respectively to upstanding plates 45, 46 upon the carriages 29, 30 and are connected at their opposite ends to a plate projecting upwardly from the carriage 44.

70 The shafts 25, and 26 are provided with pulleys 47 and 48 with a connecting belt 49 for driving the same in synchronism. It will however be understood that other well known means may be provided for accomplishing this purpose. Since it is absolutely necessary that the shafts 25, 26, be driven 80 in synchronism the belt and pulley connections are selected as any variation in rotation of the shafts will be accompanied by a slipping of the belt which will correct an improper driving relation. Power may be 85 applied to one of the shafts through a pulley 50 driven by a belt running over a suitable driving pulley on any convenient portion of the shaft.

90 By the construction above described it will be obvious that the clearers will be reciprocated in unison back and forth throughout the extent of the bur pans or chutes and the burs may be discharged at either end or at both ends if so desired.

95 If the burs are to be discharged from one end only it is necessary that the clearers shall be rendered inoperative during their return reciprocation and this is accomplished in the present invention in substantially the same manner as illustrated in our prior patent by providing each carriage with pivotally mounted clearers which are raised into inoperative positions by a member which is engaged by a bunter at the end 100 of the working reciprocation; the clearers being returned to operative position by a similar bunter at the opposite end of the machine.

105 In the illustrative embodiment of the invention disclosed herein the carriages, 29, 30 are conveniently constructed in the form of two part sleeves embracing the shafts, the upper half sleeve providing the upwardly extending plates 45 or 46 to which the bridges are attached while the lower half sleeve is provided with a depending plate 51. The plate 51 may be provided at its upper edges with bosses 52 adapted to support a pintle 53 extending through straps 110 54, 55 upon the upper edges of the clearers 32 thus forming a hinged connection between the edge of the plate 51 of the carriage and the clearer blades. These clearer blades may be operated in substantially the 115 same manner as disclosed in my prior patent by means of an oscillatory member having a finger to engage the under side of the clearer blade and an arm adapted to project into the path of the bunter preferably both 120 125 130

of the clearer blades being actuated simultaneously by finger members connected by gears. As illustrated herein the depending plate 51 of the carriage is provided with studs 56 upon which are pivoted the hubs 58 59 of the clearer raising fingers 60—61 the hubs 58, 59 being provided with intermeshing gears 62, 63 adapted simultaneously to raise the clearer blades when actuated in one direction and to permit the clearer blades to drop by gravity into a substantially vertical position when actuated in the opposite direction.

One of the hubs 58 or 59 is provided with an upwardly extending arm 64 adapted to engage a suitable bunter positioned in its path of travel adjacent the respective ends of the traverse shaft.

In order to maintain the clearers in elevated position during the return stroke frictional means are preferably provided for retaining the clearer actuating members in any desired elevation. In the preferred embodiment of the invention disclosed herein this is accomplished by providing the studs 56, upon which the hubs 58 or 59 are mounted, with extensions 65 and surrounding said studs with helical springs 66 adapted to bear at one end against the hub and at the other upon the base of winged nuts 67 which may be adjusted to produce a sufficient compression upon the springs 66 to give the desired amount of friction.

The bunters for controlling the members which actuate the clearers are preferably in the form of brackets having adjustments to permit vertical and lateral positioning. The bunters for the end carriages 29, 30 may conveniently be carried upon the brackets 34 which support the traverse rolls. As illustrated in Fig. 4 of the drawing the bracket 34 is provided with a downward extension 68 to which a plate 69 is connected by bolt and slot connections 70, 71 permitting vertical adjustment, the lower end of the plate 69 being offset to provide a horizontal portion 72 to which is connected the bunter 73 which may be in the form of a plate having a longitudinal slot 74 adapted to receive a bolt 75 by means of which the plate 73 may be adjustably connected to the plate 69. It will thus be observed that the bunter 73 may be positioned both vertically and laterally to coöperate properly with the arm 64 of the clearer actuating member at either end of the machine.

In order to provide for the actuation of the intermediate clearer a curved plate 74 may conveniently be secured to either of the brackets 34 the end of the bunter 74 extending in the path of the arm 64 of the actuator upon the intermediate carriage.

Where but two of the bur pans are provided as at the left end of the portion of the machine shown in the drawing, the car-

riages may conveniently be connected together by a suitable bridge so that the carriages will move in unison and both carriages may if desired be operated by a single traverse thereafter as will be readily understood.

It will be understood that the embodiment of our invention illustrated in the accompanying drawings is illustrative merely and that the invention may be embodied in other forms within the meaning and scope of the following claims.

Having thus described our invention, what we claim as new and desire to secure by Letters Patent is:

1. In an apparatus of the class described comprising a series of pans to receive the burs, clearers adapted to be moved longitudinally of said pans to discharge the burs therefrom, a supporting means connected to all of said clearers, means for automatically reciprocating said supporting means whereby said clearers will be actuated in unison.

2. In an apparatus of the class described comprising a bur cylinder, a series of three or more pans to receive the burs, clearers adapted to move longitudinally of said pans to discharge the burs therefrom, a rigid supporting member connecting said clearers, means for automatically reciprocating said supporting member and thereby actuating said clearers in unison, means to position operatively said clearers when reciprocated in one direction and means to render said clearers inoperative when reciprocated in the opposite direction.

3. In an apparatus of the class described comprising a bur cylinder and a series of three or more pans to receive the burs, two traverse shafts and means for rotating the same in synchronism, carriages mounted upon said shafts, a bridge connecting said carriages, clearers supported by said carriages and said bridge in operative relation to said pans, independent means for rendering each of said clearers inoperative when moved in one direction and means to restore said clearers to operative position when moved in the opposite direction.

4. In an apparatus of the class described comprising a bur cylinder and three or more pans to receive the burs, two traverse shafts lying adjacent to and in parallelism with the outer pans, means for rotating said traverse shafts in synchronism, carriages mounted upon and reciprocated thereby longitudinally by said shafts, a bridge connecting said carriages, clearers supported by said carriages and said bridge in operative relation to the respective pans of the series, means for rendering the clearers operative when moved in one direction and means for rendering the same inoperative when moved in the opposite direction.

5. In an apparatus of the class described

having a bur cylinder and a bur pan to receive the burs therefrom, means to discharge the burs from said pan consisting of a carriage mounted to travel longitudinally of said pan and means for actuating the same, 5 a normally depending clearer pivotally mounted upon said carriage in operative relation to said pan, means for raising said clearer to inoperative position and adjustable frictional instrumentalities for retaining 10 said clearer raising means in elevated or depressed position.

6. In an apparatus of the class described having a bur cylinder and a bur pan to receive the burs therefrom, a carriage mounted to travel longitudinally of said pan and means to reciprocate said carriage, a normally depending clearer pivotally mounted on said carriage, a clearer raising member 15 comprising a head pivotally mounted upon a stud projecting from said carriage and having an arm engaging said clearer and an actuating arm adapted to be oscillated to raise and lower the clearer engaging arm 20 and an adjustable frictional instrumentality engaging said head whereby the power required to actuate said clearer raising member may be varied.

7. In an apparatus of the class described comprising a bur cylinder, a bur pan to receive the burs therefrom, a carriage mounted to travel longitudinally of said pan and means for reciprocating the same, a pair of normally depending clearers pivotally 30 mounted upon said carriage in operative relation to said pan, a clearer raising member comprising a hub pivotally mounted on said carriage, a stud projecting laterally from said carriage having a stem extending beyond the upper face of said hub, a helical 35 spring on said extension, a nut screw threaded upon said extension adapted to compress said spring, an arm on said hub engaging said pivot and an actuator arm adapted to 40 be oscillated to raise and lower the clearer engaging arm.

8. In an apparatus of the class described comprising a bur cylinder and a bur pan to

receive the burs, a rotating traverse shaft and a clearer reciprocating thereby longitudinally of said bur pan; shaft supporting brackets and means for adjusting the same vertically and laterally whereby the clearer may be accurately positioned in respect to the base and sides of the pan.

9. In an apparatus of the class described comprising a bur cylinder and bur pan to receive burs therefrom, a rotating traverse shaft and a clearer reciprocated thereby longitudinally of said bur pan; means for supporting said shaft from the usual frame of the machine comprising a vertically adjustable standard and a laterally adjustable roll supporting bracket carried by said standard.

10. In an apparatus of the class described comprising a bur cylinder and a bur pan to receive burs therefrom, a rotating traverse shaft and a clearer reciprocated thereby longitudinally of said bur pan; means for supporting said shaft from the usual frame 70 of the machine comprising eye bolts secured to opposite end frames, standards having screw threaded portions passing through the eyes of said eye bolts, nuts on opposite sides of said eye bolts, and roll supporting 75 brackets secured to said standards.

11. In an apparatus of the class described comprising a bur cylinder and a bur pan to receive burs therefrom, a rotating traverse shaft and a clearer reciprocated thereby longitudinally of said bur pan; means for supporting said shaft from the usual frame of the machine comprising eye bolts secured to opposite end frames, standards provided with enlarged shouldered heads and having 80 screw threaded portions passing through the eyes of said eye bolts, nuts on opposite sides of said eye bolts, roll supporting brackets carried in the shoulders of said brackets and 85 adjustably secured thereto by bolt and slot 90 connections.

In testimony whereof, we have signed our names to this specification.

WRIGHT PRESTWICH.
ERNEST PRESTWICH.
